Application January 3, 1942, Serial No. 425,504

7 Claims. (Cl. 173—328)

1

This invention relates to electrical connectors and relates more particularly to connectors for facilitating the connecting and disconnecting of electrical circuits in aircraft, radio equipment, and the like. A general object of this invention is to provide an electrical connector of the character referred to which materially reduces the labor and time required in connecting or assembling the connector in the circuits.

The electrical connectors employed in military and naval aircraft usually embody a receptacle and a plug each of which usually carries a number of contacts, the contacts of one being socket contacts and the contacts of the other being plug contacts. The contacts are often quite small and close together and are secured in phenolic inserts. It has been the universal practice to either mold the contacts in the phenolic inserts or to provide the contacts with external flanges which are clamped between sections of the inserts. These modes of fixing the contacts in the inserts make it necessary to secure the wires to the contacts after the contacts are secured in their inserts. It is a difficult tedious operation to solder the plurality of wires to the individual closely positioned contacts and in the event of error it is impossible to remove the individual contacts to correct the error. With the contacts preassembled in the connector, as has been the universal practice, it is impossible to crimp the contacts onto their wires and it has always been necessary to resort to the slow difficult soldering operations.

Another and important object of this invention is to provide a connector suitable for use on aircraft, in radio circuits, etc., and embodying contacts that may be installed in the receptacle or plug, as the case may be, after having been secured to their respective wires. The connectors of the present invention may be constructed to fully meet the United States Army and Navy specifications for electrical aircraft connectors and are characterized by contacts which may be secured to their wires by soldering, crimping, or other means and then installed in their respective inserts. The contacts of the present invention may be secured to their wires independently of the connector, for example, they may be secured to the wires at a bench or on a mass production basis by any approved means such as soldering or crimping, and merely inserted in the openings in the inserts of the connectors to complete the assembly, following the pulling of the wires through the conduits, etc. This entirely eliminates the difficult time consuming operations of

2

individually soldering the wires to contacts already fixed in close proximity to one another in the connector assemblies.

Another object of this invention is to provide a connector of the present invention in which the individual contacts may be readily removed from their connector inserts in the event of error, breakage, or the like.

Another object of this invention is to provide a connector of the character mentioned in which the contacts are approximately the same diameter as their wires so that they may be readily run through the conduits on the wires thus further simplifying the installation procedure.

Another object of this invention is to provide a connector of the character referred to, embodying novel lock means or retaining means which automatically engage and lock the contacts when they are inserted in the openings of the inserts.

The automatic lock or retaining means is dependable and sturdy and capable of effectively resisting removal or displacement of the contacts. The lock means or retaining means of the invention offers resistance to removal of the contacts far in excess of the requirements of the United States Army and Navy specifications.

A further object of this invention is to provide a connector of the character mentioned in which the inserts, contacts and contact retaining means are simple and inexpensive and adapted for use in standard receptacle and plug shells.

The various objects and features of my invention will be fully understood from the following detailed description of typical preferred forms and applications of my invention, throughout which description reference is made to the accompanying drawings, in which:

Fig. 1 is a central longitudinal detailed sectional view of the receptacle assembly of one form of the invention. Fig. 2 is a central longitudinal detailed sectional view of the plug assembly of this form of the invention. Fig. 3 is an end view of the receptacle, being a view taken as indicated by line 3—3 on Fig. 1. Fig. 4 is a side elevation of one of the plug contacts prior to its connection with the wire. Fig. 5 is an enlarged perspective view of the contact retaining spring. Fig. 6 is an enlarged perspective view of the rear section of one of the inserts. Fig. 7 is an enlarged fragmentary longitudinal sectional view of one of the connector assemblies illustrating the spring member. Fig. 8 is a view similar to Fig. 1 illustrating another form of the invention. Fig. 9 is an enlarged elevational view of the contact retaining ring of the structure illus-

trated in Fig. 8 and Fig. 10 is a view similar to Fig. 1 illustrating still another form of the invention.

The embodiment of the invention illustrated in Figs. 1 to 7, inclusive, may be said to comprise, generally, a receptacle 10, an insert 11 in the receptacle having contact receiving openings, pins or contacts 12, and means 13 for retaining or locking the contacts 12 in the openings; and a plug 14 comprising a shell 15, an insert 16 in the shell having contact receiving openings, sockets or contacts 17 to be inserted in the openings, and means 18 for locking or retaining the contacts 17 in the openings.

The receptacle and plug structures or assemblies may be varied to adapt the connector for different uses and installations. In the drawings I have shown a typical form of general plug and receptacle assembly, it being understood that the invention is not to be construed as limited or restricted to the specific form or details herein described but is to be taken as including features or modifications that may fall within the scope of the claims.

The receptacle 10 includes a shell 19 of aluminum alloy, or the like, adapted for rigid attachment to a support or the like. The shell 19 is an elongate tubular member provided between its ends with an external flange 20 having openings 21 for receiving securing elements, not shown. The interior of the shell 19 is formed or shaped to hold the insert 11 and to receive a portion of the plug 14. An inwardly projecting annular flange 22 is formed in the shell 19 substantially midway between its ends. The portion of the shell 19 inwardly or forwardly of the flange 22 is adapted to receive the entering portion of the plug 14 while the outer or rear part of the shell occurring behind the flange 22 contains or carries the insert 11. One or more spaced longitudinal ribs or keys 23 are provided in the forward plug receiving portion of the shell 19. The rear or outer portion of the shell 19 which carries the insert 11 has a similar rib or key 24 extending rearwardly from the flange 22. The keys 23 and 24 are preferably, though not necessarily, flat sided.

The insert 11 is provided to receive or carry the contacts 12. The insert is formed of phenolic material or other effective dielectric suitable for the purpose. In accordance with the invention, the insert 11 is sectional, comprising an insert body 25 and a plate or disc 26 at the outer end of the body. The body 25 and disc 26 are cylindrical and proportioned to rather accurately fit in the shell 19 and have grooves 27 for receiving the key 24. The inner corner of the insert body 25 has an annular groove 28 for receiving the flange 22. The flange 22 limits inward movement of the insert 11 and the end of the insert body 25 may be flush with the forward face of the flange 22. Means is provided for removably holding or locking the insert body 25 and disc 26 in the shell 19. This means comprises a split spring ring 29 snapped into a groove 30 formed in the shell 19 adjacent its outer end. The spring ring or snap ring 29 holds the disc 26 tightly against the face of the body 25 and holds the insert body 25 in close engagement with the flange 22.

The insert 11, consisting of the insert body 25 and disc 26, is provided with longitudinal or axial openings for receiving the contacts 12. The number and disposition of the openings 31 vary with different connectors. In the case illustrated there is a central opening 31 and a circular series

of spaced openings 31 surrounding the central opening in spaced relation thereto. The openings 31 are spaced apart to the best advantage to obtain the greatest surface leakage areas between adjacent openings and are spaced substantial distances from the shell 19. The several openings 31 are shown identical in size and shape but in many instances the openings are of different diameters to receive contacts of different current carrying capacities. For the present purpose it will be assumed that the openings 31, as initially formed, extend completely through the insert 11, that is, they extend completely through the body 25 and disc 26.

The openings 31 are stepped or shouldered to receive the contacts 12 and to house the means 13. Sockets 32 are formed in the rear or outer ends of those portions of the openings 31 which pass through the insert bodies 25. The openings 31 are reduced in diameter in a plane spaced forwardly from the sockets 32 to have rearwardly facing shoulders 33. The openings 31 are further reduced in diameter in a plane spaced forwardly from the shoulders 33 to have second shoulders 34. As best illustrated in Figs. 1 and 7 of the drawings, the disc 26 has bosses 35 for fitting the sockets 32. The sockets 32 and the bosses 35 increase the surface leakage distances between the adjacent openings 31. The portions of the openings 31 which pass through the disc 26 and its bosses 35 are of substantially the same diameter as those portions of the openings 31 located between the shoulders 33 and 34 so that the ends of the bosses 35 constitute annular shoulders 36 on the walls of the openings which oppose the shoulders 33.

In most instances it will be preferred to initially form the openings 31 completely through both the insert body 25 and disc 26. In some cases, however, it may be desirable to leave the extreme forward ends of the openings 31 or of some of the openings 31 closed to be broken or drilled out when it is determined how many openings and which of the openings are to be required.

The contacts 12 are elongate elements of a selected or required conductive material. The receptacle 10 may be equipped with either pin type or socket type contacts. In the particular case illustrated the receptacle 10 is provided with pin type contacts 12. The active portions of the pin contacts 12, which project from the inner face of the insert body 25, are plain cylindrical parts with rounded forward ends. Each pin or contact 12 has two spaced annular enlargements or flanges 37 and 38. The flanges 37 are adapted to engage against the shoulders 34 and when engaging the shoulders 34 their rear faces are flush with the shoulders 33. This is illustrated in Fig. 1. It will be observed that the flanges 37 engaging with the shoulders 34 limit the forward or inward movement of the contacts 12. The enlargements or flanges 38 fit those portions of the openings 31 which pass through the disc 26. The forward ends of the flanges 38 lie flush with the shoulders 36. The contacts 12 further have rear end parts which project from the disc 26. These parts are formed for ready connection with the wires W. They may be formed for crimping, soldering or modes of connection with the wires. In the case illustrated, I have shown the rear parts of the pins or contacts 12 formed with solder cups 39. Fig. 1 of the drawings shows how the bared portions of the wires W may be soldered in the cups 39. It will be observed that the contacts 12 are simple readily formed elements.

The means 13 are important elements of the invention. In the form of the invention being described the means 13 comprise simple spring lock members 40 which freely allow the introduction of the pins or contacts 12 into the openings 31 and which positively prevent the rearward withdrawal of the contacts from the openings. The lock members 40 are tubular or annular generally cylindrical elements arranged in the openings 31 between the shoulders 33 and 36. The lock members 40 are proportioned so that their opposite ends cooperate with the shoulders 33 and 36 with little or no clearance. The rear ends of the members 40, that is, the ends of the members 40 which cooperate with the shoulders 36 are plain and are adapted to effectively cooperate with the shoulders. The forward end portions of the lock members 40 have spaced pairs of slits or cuts 41 and the stock or material between the adjacent cuts 41 are turned or bent inwardly to form flexible resilient fingers 42. The fingers 42 slope inwardly and forwardly. See Figs. 1, 5, and 7. The portions of the members 40 between the spaced fingers 42 are plain or cylindrical and, as above described, the forward ends of the members 40 cooperate with the shoulders 33. The spring members or lock members 40 are formed to expand through their inherent resiliency to closely hug the walls of the openings 31 between the shoulders 33 and 36. With the members 40 thus engaged against the walls of the openings 31 their fingers 42 project inwardly and forwardly for cooperation with the flanges 37 of the contacts 12.

The lock members 40 are assembled in the openings 31 when the insert 11 is assembled and secured in the shell 19. When a pin or contact 12 has been crimped or soldered to its wire W it may be introduced into its opening 31. The contact is merely pressed forwardly into the opening. The contact is proportioned to freely move forwardly through the opening 31 and as the contact moves forwardly the flange 37 comes into engagement with the spring fingers 42. The entering end of the flange 37 cooperates with the sloping inner surfaces of the spring fingers 42 and this engagement flexes the spring fingers outwardly. Thus, the spring fingers 42 are flexed outwardly to allow the flange 37 to move forwardly to its position against the shoulder 34. When the contact 12 has been pushed forwardly to engage the flange 37 with the shoulder 34, the spring fingers 42 automatically snap inwardly behind the flange 37. The spring fingers engaging the rear side of the flange 37 latch or lock the contact 12 against outward or rearward movement. In this connection it will be observed that the spring fingers 42 and the member 40 operate under compression to prevent the rearward movement of the contact 12 and are thus able to offer high resistance to rearward movement of the contact 12. The spring fingers 42 engage inwardly against the body of the contact 12 and are thus prevented from springing inwardly. A rearward force on the contact 12 may tend to force the spring fingers inwardly but, as just described, this movement is impossible. There is no tendency for the spring fingers to flex outwardly under an outward or rearward pull on the contact 12. The lock member 40 forms a strong dependable means for automatically latching the contact 12 against rearward displacement and is automatically operative when the contact is merely inserted to its final position in its opening 31. It is to be understood that each of the several openings 31 is equipped with a

lock member 40 and that the contacts 12 may be automatically locked in the insert 11 in the manner just described by merely inserting them forwardly into their openings 31.

- 5 The plug 14 is adapted to be plugged into or introduced into the receptacle 10 to complete the several electrical circuits. The shell 15 of the plug 14 is an elongate tubular member of aluminum alloy, or the like, and its forward end portion is proportioned to enter the shell 19 of the receptacle 10 with suitable clearance. The forward portion of the shell 15 has one or more grooves 43 for receiving the ribs or keys 23 to prevent relative turning between the shells of the receptacle and plug when the connector is made up. The rear portion of the shell 15 has an internal rib or key 44. A rearwardly facing annular shoulder 45 is provided in the shell 15 between its ends.
- 10 The plug 14 is provided with suitable means for making a threaded connection with the receptacle 10 and for connecting with a conduit or other fitting. In the particular case illustrated, a coupling nut 46 surrounds the forward portion of the shell 15 and is rotatably connected with the shell by a lock ring or spring ring 47 engaged in registering grooves 48 in the nut and the rear portion of the shell which is enlarged in external diameter. The nut 46 is freely rotatable with respect to the shell 15. The forward portion of the nut 46 has an internal thread 49 for mating with an external thread 50 on the forward portion of the receptacle shell 19. It will be readily seen how the nut 46 may be employed to make up or connect the receptacle and plug. The rear portion of the plug 14 may be equipped with a swivel coupling means including a sleeve 51 rotatably connected with the shell 15 by a spring ring 52 engaged in registering grooves 53 in the shell and sleeve. An adaptor 54 is threaded in the rear portion of the sleeve 51 and has an external thread for engagement with a conduit or fitting. The forward end of the adaptor 54 has engagement with the rear end of the shell 15 and these engaging surfaces may be knurled.
- 15 The insert 16 receives or carries the sockets or contacts 17 of the plug 14. The insert 16 is formed of phenolic material or other appropriate dielectric and is similar to the insert 11 of the receptacle 10, being a sectional element comprising a body 55 and a rear section or disc 56. The insert body 55 is a cylindrical part which occupies the major portion of the shell 15. The forward face of the insert body 55 is flush with the forward end of the shell 15 and the body 55 has a forwardly facing shoulder 57 engaging with the shoulder 45 to hold the insert against forward movement in the shell. The disc 56 may be identical with the above described disc 26 and is engaged against the rear end of the body 55. A spring ring 59 is removably engaged in an internal groove in the rear portion of the shell 15 and cooperates with the disc 56 to hold the insert 16 against rearward movement. The insert body 55 and disc 56 have a longitudinal groove for receiving the key 44 whereby the insert is held against turning in the shell 15.
- 20 The sectional insert 16, just described, has longitudinal openings 60 for receiving the contacts 17. The openings 60 are all identical and have the same spaced relationship as the openings 31 to be in alignment therewith when the connector is made up. It is to be understood that in many cases the openings 31 are of different diameters to receive contacts of different current carrying
- 25
- 30
- 35
- 40
- 45
- 50
- 55
- 60
- 65
- 70
- 75

capacity. Each opening 60 has a rearwardly facing annular shoulder 61 adjacent its rear end and a rearwardly facing annular shoulder 62 spaced forwardly from the shoulder 61. Further, each opening 60 has a rearwardly facing annular shoulder 63 adjacent its forward end. The disc 56 has bosses 64 similar to or identical with the bosses 35 and these bosses enter the rear portions of the openings 60 to engage with the shoulders 61. The forward ends of the bosses 64 constitute shoulders which are in spaced opposing relations to the shoulders 62. The enlarged rear portions of the openings 60 and the bosses 64 provide increased surface leakage or creepage areas between the spaced openings 60.

The sockets or contacts 17 are elongate elements adapted to be connected with their respective wires W and adapted to be inserted in the openings 60 to be locked therein by the means 18. Where the receptacle 10 carries pin contacts, as above described, the contacts 17 of the plug 14 are socket contacts. The socket contacts 17 are formed of selected or approved conductive material and their forward ends are formed to receive and grip the exposed forward parts of the pin contacts 12. The forward portions of the contacts 17 have longitudinal sockets or openings 67 for receiving the pin contacts 12 and have spaced longitudinal slots 65 leaving spring fingers 66. The openings 67 are proportioned to closely receive the forward parts of the contacts 12, the spring fingers 66 flexing from their bases when the sets of contacts are engaged. The spring fingers 66 engage the contacts 12 with sufficient gripping force to maintain the required engagement. The contacts 17 are formed with rearwardly facing annular shoulders 68 which lie in the same planes as the shoulders 62 and have collars or flanges 69 which occupy the openings in the bosses 64 to have their forward ends flush with the forward ends of the bosses. The rear portions of the contacts 17 which project beyond the disc 56 are formed for ready connection with the wires W. In the case illustrated the rear parts of the contacts 17 have solder cups 70. The contacts 17 may be crimped or soldered on their respective wires W prior to introduction into the connector assembly and, therefore, may be applied to their wires at a bench or in a machine remote from the connector.

The means 18 for locking or retaining the contacts 17 in the plug 14 are identical with the means 13 comprising lock members 40. The lock members 40 employed in the plug 14 being identical with the lock members 40 above described are provided with corresponding reference numerals. The lock members 40 are arranged in the openings 60 to have their plain rear ends engage with the forward ends of the bosses 64 and to have their forward ends engage with the shoulders 68. The lock members 40 are formed to hug the walls of the opening 60 by reason of their resiliency. When a contact 17 is inserted forwardly into its opening 60 the forward portion of the contact freely passes through the boss 64 and into the lock member 40. The entering end of the contact 17 engages the spring fingers 42 and flexes the fingers outwardly. The contact is readily pushed forward until its forward end engages the shoulder 63 at which time the shoulder 62 comes coincident with the shoulder 68. This allows the spring fingers 42 to snap inwardly into engagement with the shoulder 62. Thus, the contact 17 is locked in its opening 60.

The pin and socket contacts 12 and 17 shown

are of the type employed in the approved Army and Navy connectors. It is to be understood that the connector of the invention may embody other types of contacts as required or as made necessary by installation conditions.

It is believed that the operation of the connector illustrated in Figs. 1 to 7, inclusive, will be readily understood from the foregoing detailed description. The receptacle 10 and plug 14 are 10 preferably supplied to the user completely assembled except for the contacts 12 and 17. The contacts 12 and 17 are supplied separately in order that they may be applied to their respective wires W. It is important to note that the free independent contacts 12 may be readily secured to their wires by soldering, crimping, or other appropriate means entirely independent of the connector and these operations may be performed at a bench or in a machine.

15 20 When the contacts 12 are to be engaged in their receptacle 10 and plug 14 they are merely passed forwardly through their openings 31 and 60, as above described. When this is done the lock members 40 automatically lock the contacts in 25 the inserts 11 and 16. In the event there has been an error or if for any other reason it is desirable to withdraw a contact, the spring ring 29 or 59, as the case may be, is disengaged from its groove permitting the rearward removal of the 30 entire insert 11 or 16 and permitting the rearward movement of the disc 26 or 56. Upon rearward movement of the disc with respect to the insert body 25 or 55 the contact is moved rearwardly carrying with it the lock member 40. The lock member 40, upon disengagement from the opening 31 or 60, springs open and drops from the contact, permitting free disengagement of the contact. Thus, one or more of the contacts may be easily and quickly removed from the connector 35 40 without difficulty and without breaking any of the parts.

Figs. 8 and 9 of the drawings illustrate an embodiment of the invention having a modified or alternative form of lock means for retaining the contacts in their inserts. The connector assembly illustrated in Figs. 7 and 8 is a receptacle having a shell 19^a similar to or identical with the shell 19, an insert 11^a similar to the insert 11 and a contact 12^a. The insert 11^a includes a body 25^a 45 and a rear section or disc 26^a removably engaged against the rear end of the body. The insert is held in the shell 19^a by a spring ring 30^a engaged in a groove in the shell. The insert 11^a is formed of phenolic material, or the like, and has one or more longitudinal openings for receiving the contacts 12^a. These openings 31^a may be of selected disposition and spacing. The several openings 31^a pass completely through the body 25^a and disc 26^a of the insert 11^a. Each opening 31^a 50 has a rearwardly facing annular shoulder 70 between its ends and the rear portion of each opening is enlarged in diameter to receive the boss 35^a of the disc 26^a.

The contacts 12^a are elongate members of conductive material and, in the case illustrated, are pin contacts, it being understood that they may be socket contacts. Each contact 12^a is provided between its ends with an enlarged portion 71 having a tapered forward end 72. An annular groove 73 is provided in each enlarged portion 71. The grooves 73 are located to occur between the shoulders 70 and the forward ends of the bosses 35^a. The rear portions of the contacts 12^a which project rearwardly from the insert 11^a are formed

for ready connection with their wires, for example, they may have solder cups 74.

The lock means of the structure illustrated in Figs. 8 and 9 comprises split washers or spring rings 75. The rings 75 are arranged in the openings 31^a between the shoulders 70 and the forward ends of the bosses 35^a. The rings 75 are resilient and are constructed to normally assume a diameter which closely engages in the grooves 73.

In employing the structure illustrated in Figs. 8 and 9 the contacts 12^a are secured to their respective wires and when they are to be installed in the coupler assembly they are merely pushed forwardly through the openings 31^a. The reduced forward portions of the contacts 12^a freely pass through the rings 75. When the tapered surfaces 72 engage the rings 75, the rings are spread so that the enlarged contact portions 71 may enter the rings. When the contacts 71 reach their final positions the lock rings 75 snap into the grooves 73. The engagement of the rings 75 in the grooves 73 effectively lock the contacts 12^a in place. The spring rings 75 engage in the grooves 73 and project outwardly to have engagement with the shoulders 70 and the ends of the bosses 35^a. These engagements dependably secure the contacts 12^a in place. The contacts 12^a may be removed from the receptacle by releasing the spring ring 30^a and withdrawing the disc 26^a rearwardly to expose the spring rings 75 for disengagement from their contacts.

It is to be understood that the complementary section or assembly of the connector may have its contacts secured in the insert in the same manner as the contacts 12^a.

Fig. 10 of the drawings illustrates still another form of the invention for retaining or locking the contacts in the connector assembly. The structure of Fig. 10 includes a shell 19^b similar to the shell 19, an insert 11^b and contacts 12^b. The insert 11^b includes a body 25^b and a rear disc 26^b both of phenolic material, or the equivalent. The insert 25^b engages forwardly against a shoulder 22^b on the interior of the shell 19^b and a spring ring 30^b is engaged in an annular groove in the shell to hold the insert against rearward movement. The insert 11^b has one or more openings 31^b for receiving the contacts 12^b. The several openings 31^b pass completely through the insert. The major rear portions of the openings 31^b are enlarged in diameter providing rearwardly facing annular shoulders 80 adjacent the forward ends of the openings. The openings 31^b are enlarged or flared as at 81 at the rear surface of the insert body 25^b.

The contacts 12^b are substantially the same as the contacts 12^a being elongate members of conductive material designed to be inserted in the openings 31^b and provided with collars or enlarged portions 82. These enlarged portions 82 are designed to occupy the enlarged rear portions of the openings 31^b and the forward ends of the enlarged portions 82 are engageable with the shoulders 80 to limit the forward movement of the contacts. Each enlarged contact portion 82 has an annular groove 83.

The contact retaining means of the structure illustrated in Fig. 10 comprises a sheet or plate 84 of flexible resilient material engaged and held between the insert body 25^b and the disc 26^b. The disc or plate 84 is formed of synthetic rubber or other approved flexible resilient material. Openings 85 are formed in the plate 84 to register with the openings 31^b. The openings 85 are con-

siderably smaller in diameter than the rear portions of the openings 31^b. When a contact 12^b is inserted forwardly into its opening 31^b the reduced front end of the contact freely passes through the openings 31^b and 85. The enlarged contact portion 82 is considerably larger in diameter than the opening 85 and when the portion 82 engages the plate 84 the adjacent portion of the plate is flexed forwardly into the flared opening part 81. The forward end of the enlarged contact portion 82 is bevelled and may be forced through the reduced opening 85 by applying forward pressure to the contact. The contact 12^b is pushed forwardly until the forward end of the portion 82 engages the shoulder 80 at which time the groove 83 receives the flexible resilient plate 84. The material of the plate 84 springs into and occupies the groove 83, as illustrated in the drawings. Thus, the plate 84 forms a lock or retainer for preventing rearward withdrawal of the contact 12^b.

Having described typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. In an electrical connector, a body of dielectric material having an opening, a contact to be inserted in the opening, cooperable shoulders on the wall of the opening and the contact for limiting movement of the contact in one direction, opposing shoulders on the wall of the opening and the contact and spaced apart longitudinally of the contact, and a longitudinally split flexible resilient sleeve member normally held in the opening between the last named shoulders and acting to positively retain the contact in the opening when it is introduced into the opening.

2. In an electrical connector, a body of dielectric material having an opening, a contact to be installed in the opening, cooperable shoulders on the wall of the opening and the contact for limiting inward movement of the contact, opposing shoulders on the wall of the opening and the contact, and an elongate split sleeve-shaped spring member normally frictionally carried in the opening for cooperating with said opposing shoulders, when the contact is inserted in the opening and acting under longitudinal compression to prevent outward movement of the contact the said member being confined against displacement from the contact when in the opening.

3. In an electrical connector, a body having an opening, a resilient longitudinally split sleeve lock member normally confined in the opening and having fingers normally sloping forward and slightly inward, a contact to be installed in the opening, and an enlarged part on the contact for limiting inward movement of the contact into the opening and adapted to be moved inwardly past said fingers by deflecting them radially, said part presenting a rear surface engageable by the ends of said fingers to prevent rearward movement of the contact.

4. An electrical connector assembly comprising a shell, an insert of dielectric material in the shell having an opening, the insert comprising a body, and a plate removably held at one end of the body, spaced opposing shoulders on the wall of the opening, one shoulder being on the body, the other being on the plate, an elongate

sleeve-shaped spring lock member normally frictionally carried in the opening between the shoulders, a contact to be installed in the opening and a part on the contact engaged by said member so that said member acts under longitudinal compression to retain the contact in the opening.

5. An electrical connector assembly comprising a shell, an insert in the shell having an opening, the insert comprising a body, and a plate removable from the body, spaced opposing shoulders on the wall of the opening, one shoulder being on the body, the other being on the plate, a spring lock sleeve member normally frictionally carried in the opening and held between the shoulders, a contact to be installed in the opening and a part on the contact engaged by said member whereby said contact is retained in the opening, the lock member being longitudinally split and tending to expand so that it disengages from the contact when removed from the opening.

6. An electrical connector assembly comprising a shell, an insert in the shell having an opening, the insert comprising a body, and a plate removably held at one end of the body, a boss on the plate entering an enlargement of the opening at one end thereof, the inner end of the boss forming a shoulder on the wall of the opening, there being a second shoulder on the wall of the opening opposing the first named shoulder and spaced therefrom longitudinally of the opening, an elongate tubular spring lock member held between said shoulders and having a spring finger radially inward of the shoulders, and a contact to be installed in said opening and having a collar part engaged by said finger to lock the contact in the opening.

7. An electrical connector including, a body having two separable sections normally held to- 40

gether as a unit, there being an opening in the body with opposed shoulders one on each section of the body, a longitudinally split spring tubular member normally frictionally carried in the opening between the shoulders and having a longitudinally disposed spring tongue facing the inner end of the opening, and a contact to be inserted in the opening and having a shoulder to be moved past the tongue by deflecting it radially and cooperating with the tongue to prevent withdrawal of the contact from the opening.

RAY W. GUDIE.
